UNITED STATES PATENT OFFICE.

WILLIAM G. TAYLOR, OF HULTON, PENNSYLVANIA.

DESIGN FOR A GAS-STOVE.

SPECIFICATION forming part of Design No. 26,937, dated April 20, 1897.

Application filed March 10, 1897. Serial No. 626,885. Term of patent 14 years.

To all whom it may concern:

Be it known that I, WILLIAM G. TAYLOR, of Hulton, in the county of Allegheny and State of Pennsylvania, have invented a new and original Design for Gas-Stoves, of which the following is a full, clear, and exact description, reference being had to the accompanying drawings, forming part of this specification, in which—

10 Figure 1 shows in front elevation a gas-stove embodying my design. Fig. 2 is a rear elevation. Fig. 3 is a top plan view, and Fig. 4 is a bottom plan view, thereof.

15 My design consists in a gas-stove having the shape and form in front elevation and plan substantially as herein shown and described.

As shown in the drawings, 2 represents the face-plate of the stove, having series of perforations 3, set in grooves 4, between parallel 20 rows of woolly fiber 5. At the sides and bottom are curved cheek-pieces 6, surrounded by a marginal plate or frame 7. The shape of the stove in plan view is as shown in Fig. 3.

I claim—

25 The design for gas-stoves substantially as herein shown and described.

In testimony whereof I have hereunto set my hand.

WILLIAM G. TAYLOR.
